United States Patent Office.

S. P. SEDGWICK, OF WHEATON, ILLINOIS.

Letters Patent No. 76,832, dated April 14, 1868,

IMPROVED MEDICINE.

The Schedule referred to in these Letters Patent and making part of the same.

TO ALL WHOM IT MAY CONCERN:

Be it known that I, S. P. SEDGWICK, of Wheaton, in the county of Du Page, and State of Illinois, have invented a new and efficient Specific for Scarlet Fever and Diphtheria; and I do hereby declare that the following is a full, clear, and exact description thereof, which will enable those skilled in the art to make and use the same.

The within-described medicine, for the cure of scarlet fever and diphtheria, is prepared and believed to be efficacious upon the principle that whatever the remote cause of these diseases may be, whether epidemic or contagious, the immediate proximate cause is a viscid, acrid, glutinous mucus lining the stomach, and that if this is removed by a remedy that will not operate as physic, and will, at the same time, change the tone of the stomach so that it will not again secrete the mucus aforesaid, the patient will recover.

I prepare the medicine as follows:

Sulphate of copper, or acetate of copper, half ounce.

Ipecac, half ounce.

These substances are well pulverized and mixed, and into this mixture are put six ounces of strong sage tea, sweetened with sugar, and a tablespoonful of alcohol is added to the whole.

One ounce of this is given the patient every fifteen minutes, until the patient has vomited freely two or three times, warm drinks being given in the mean time.

If the mucous substance is discharged freely, and then the warm drinks only are ejected, it is sufficient.

If the mucus is not discharged, the emetic is to be repeated every five or six hours until that result is attained.

Before taking the emetic, the patient is to be prepared, as in other cases, by having the extremities warmed and the system in a state of as equal circulation as possible.

The medicine is to be used as a gargle for the throat in case of ulcers therein; and, as the mucus is acid, after the operation of the emetic, I give, every two or three hours, a dessert-spoonful of the following mixture:

Bicarbonate of soda, one teaspoonful.

Paregoric, one tablespoonful.

Water, half a pint.

Loaf-sugar, half an ounce.

I claim as new, and desire to secure by Letters Patent—

The medicine or specific, composed of the ingredients above in the proportion as set forth, for the purpose specified.

Witnesses:

E. W. FISHER,

G. B. VA DINE.
